Albert Wiss
INVENTOR

UNITED STATES PATENT OFFICE.

ALBERT WISS, OF CORTLANDT TOWNSHIP, WESTCHESTER COUNTY, NEW YORK.

DESIGN FOR AN EMBLEM, BROOCH, BUTTON, FOB, BADGE, CHARM, STICK-PIN, OR SIMILAR ARTICLE.

52,296.

Specification for Design.

Patented Aug. 20, 1918.

Application filed February 27, 1918. Serial No. 219,520. Term of patent 3½ years.

To all whom it may concern:

Be it known that I, ALBERT WISS, a citizen of the United States, residing in Cortlandt township, in the county of Westchester and State of New York, have invented a new, original, and ornamental Design for an Emblem, Brooch, Button, Fob, Badge, Charm, Stick - Pin, or Similar Article, as shown, of which the following is a specification, reference being had to the accompanying drawing, forming part thereof.

The figure is a plan view of an emblem, showing my new design.

I claim:

The ornamental design for an emblem, brooch, button, fob, badge, charm, stick pin, or similar article as shown.

ALBERT WISS.
